(57) **CLAIM**

I claim the ornamental design for a lamp, as shown and described.

DESCRIPTION

FIG. 1 is a top perspective view of a lamp.

FIG. 2 is a bottom perspective view thereof.

FIG. 3 is a left side elevation view thereof, the right side elevation view being a mirror view of the left side elevation view.

FIG. 4 is a front side elevation view thereof.

FIG. 5 is a rear side elevation view thereof.

FIG. 6 is a top view thereof; and,

FIG. 7 is a bottom view thereof.

The broken lines are shown for the purpose of illustrating parts of the article that form no part of the claim.
